UNITED STATES PATENT OFFICE.

JOHN J. WARREN, OF BROWNVILLE, NEW YORK.

METHOD AND APPARATUS FOR MAKING COLOR-BLENDED WALL PAPER.

Application filed May 8, 1923. Serial No. 637,423.

To all whom it may concern:

Be it known that I, JOHN J. WARREN, a citizen of the United States, residing at Brownville, in the county of Jefferson, State 5 of New York, have invented certain new and useful Improvements in Methods and Apparatus for Making Color-Blended Wall Paper; and I do hereby declare the following to be a full, clear, and exact description 10 of the invention, such as will enable others skilled in the art to which it appertains to make and use the same.

This invention relates to color blending papers, particularly wall papers.

15 The so-called color blend effects on paper are produced by dropping vari-colored dyes upon the paper web as it passes over the Fourdrinier wires, and it is the usual practice to supply these dyes through perforated 20 pipes extending across the machine. I have found that the drops of dye dropping upon the soft surface of the web strike through and do not give a soft harmonious blend. This result is further aggravated by the 25 tendency of the dye drops to run together along the under side of the pipes and form very large drops which fall upon the web at widely spaced intervals. In attempting to color blend the pulp blended paper de- 30 scribed in my U. S. Patent No. 1,344,570, I experienced these difficulties and found that the blended paper could not be successfully hung; that is, the color spots were so large and pronounced that two strips of the paper 35 hung side by side on the wall would not match, and produced a barred or streaked effect. It is, therefore, the object of the present invention to devise improved ways and means for producing a soft, diffuse 40 color blended paper, particularly a color blended pulp blended paper well adapted for wall hanging.

In attaining this object, I have done two things. First, I have improved the pipe 45 through which the dye or color solution is applied, constructing it so that the drops must fall individually and cannot coalesce along the bottom of the pipe. Second, I have applied the dye at just the right place; 50 this place being upon the apron over which the pulp blending stock flows from its blend box onto the web.

The accompanying drawings illustrate dia- 55 grammatically a preferred embodiment of a machine for practicing my invention. In these drawings, Fig. 1 is an elevation of the

wet end of a Fourdrinier paper machine equipped with a blend box for pulp blending and also with means for color blending in accordance with the present invention; 60 Fig. 2 is an enlarged sectional detail through the forward end of the pulp blending box and the apron over which the blend stock flows onto the web and through the color 65 pipes; Fig. 3 is an elevation of the color piping looking in the direction of the arrow of Fig. 2; and Figs. 4, 5 and 6 are details of various types of color pipes designed to discharge individual drops of color solution.

As shown in Fig. 1, the paper stock is de- 70 livered through a pipe 1 from a source of supply (not shown) to a flat screen 2 from which the screened stock is conducted by a pipe 4 to a flow box 5, where it passes around baffles 6 onto the Fourdrinier wire 7 in the 75 usual manner. As disclosed in my United States Patent No. 1,344,570, I prefer to add wood-flour to the base stock, thus making the base of the so-called oatmeal type. This woodflour is conducted by a pipe 8 from a 80 source of supply (not shown) to a union with the pipe 4, so that the paper stock and wood flour pass together into the flow box 5, where they are more thoroughly mixed 85 before flowing onto the wire apron. The blending stock, a very dilute solution of sulphite pulp, is supplied by a pipe 9 from a source of supply (not shown) to a blending box 10 where it passes around a series of baffles 11, and thence over an apron or fac- 90 ing slip 12 onto the paper base being formed on the wire apron, the distance between the outlets of the flow box 5 and the blending box 10, and the speed of movement of the wire apron 7, therebetween, being such that 95 the paper base is suitably formed at the time it reaches the blending box for reception of the blending stock to produce a cloudy coating of the desired appearance and effect. The foregoing is all shown and 100 described in my United States Patents Nos. 1,344,570 and 1,344,603, and in itself forms no part of the present invention.

In accordance with the present invention, I have provided in addition to the appara- 105 tus just described, a series of color pipes 13, which extend across the machine directly above the apron 12. Solutions of any non-bleeding dyes or colors, such as the aniline dyes, are supplied to these pipes from a 110 source (not shown) and permitted to drop through a series of apertures situated upon

the bottom of the pipes upon the blending stock as it passes over and down the apron. The quantity of dye thus supplied can be regulated by means of valves 14 shown on Fig. 3. Any desired color combinations can be used. I have illustrated 4 pipes and each, of course, can be used to supply a different color.

In Fig. 2, I have illustrated what I believe to be the action of the dye as it drops upon the apron. The small drops of dye striking the film of blending stock passing over the apron penetrate this and spread out over the face of the apron itself, so that when the color reaches the web, it is overlaid by the sulphite pulp of the blending stock. The result is a very soft and harmonious blend, quite distinct from the more pronounced effects obtained when the dye is dropped directly upon the web. Whether the dye acts as I have described in falling upon the apron, it is, of course, impossible to say, as a matter of fact, but the theory which I have advanced does certainly explain the undeniable difference in results which I get by applying the dye in this manner upon the apron and not directly upon the web.

Were the color pipes merely provided with a series of holes spaced along their lower sides, the small drops of color solution would cling to the pipe, and running longitudinally thereof, unite with other drops so that the distribution of color would not be good, and large drops of dye would fall at widely separated intervals, both in time and space. In accordance with this invention, I have designed a color pipe in which this coalescing action of the dye drops is impossible. As shown in Fig. 4, I have provided the lower side of the pipe with a series of small downwardly extending nozzles 15 and each drop emerging from these nozzles must fall alone. I can obtain the same results in a less expensive way by providing the pipe with a series of annular grooves 16 as shown in Fig. 5 into which the drops pass. This construction makes it difficult for the drops to migrate along the pipe. Fig. 6 shows a still further amplification of this idea; here the actual orifice is flanked with small grooves 17 which prevent movement of the drops longitudinally of the pipe.

The color blended paper made as I have described, has a softness and delicacy unattainable by any other blending method, and the color is so soft and diffuse that no difficulty is experienced in using such paper

as wall paper. It is quite possible to hang strips of the paper side by side with perfect matching.

I claim:

1. The method of making a blended wall paper which comprises flowing a pulp blending stock onto the web, the blending stock flowing over an inclined apron as it approaches the web, and applying a color solution to the blending stock as it flows over the apron.

2. The method of color blending a pulp blended wall paper made by flowing a pulp blending stock over an inclined apron and onto the paper web, which comprises dropping a color solution upon the apron as the blending stock is flowed over it.

3. The method of color blending a pulp blended wall paper made by flowing a pulp blending stock over an inclined apron and onto the paper web, which comprises dropping at fixed intervals across the web a color solution upon the apron as the blending stock is flowed over it.

4. In a machine for making blended wall paper, the combination of an inclined apron over which pulp blending stock flows onto the web, and means situated above the apron for dropping the color solution on the apron.

5. In a machine for making blended wall paper, the combination of an inclined apron over which pulp blending stock flows onto the web, and a color pipe extending across the machine above the apron for dropping a color solution upon the pulp blending stock as it flows over the apron.

6. In a machine for making blended wall paper, the combination of an inclined apron over which pulp blending stock flows onto the web, and a color pipe provided with a plurality of independent nozzles extending across the machine above the apron for dropping a color solution through the nozzles upon the pulp blending stock as it flows over the apron.

7. The method of color blending a pulp blended wall paper made by flowing a pulp blending stock over an inclined apron and onto the paper web, which comprises dropping a color solution upon the apron as the blending stock is flowed over it, the height from which the color solution is dropped being sufficient to cause the solution to strike through the flowing blending stock and underly it as the blending stock flows over the paper web.

In testimony whereof I affix my signature.
JOHN J. WARREN.
